UNITED STATES PATENT OFFICE.

OSCAR V. PAYNE, OF TAKOMA PARK, MARYLAND.

LOCKING DEVICE.

1,156,861.

Specification of Letters Patent. Patented Oct. 12, 1915.

Application filed December 5, 1914. Serial No. 875,700.

To all whom it may concern:

Be it known that I, OSCAR V. PAYNE, a citizen of the United States, residing at Takoma Park, in the county of Montgomery and State of Maryland, have invented new and useful Improvements in Locking Devices, of which the following is a specification.

My invention relates to new and useful improvements in locking devices, and has relation more particularly to a device of this general character, wherein a collar is locked to a shank or the like, and an object of the invention is to provide a novel and improved locking device whereby the collar and shank may be held against relative rotation.

It is also an object of my invention to provide a novel and improved locking device comprising a collar having upon a face thereof channels placed at predetermined positions and adapted to receive a pliable key held in a transverse cavity of a shank, said key being adapted to prevent relative rotation of the collar and shank.

One of the novel features of my invention is that the collar may be locked at any point of its axial rotation upon its shank, since there are no registering parts when the collar is in a locked position; and another novel feature of my improved device is that the collar is locked in the position last assumed, "backing-off" not being necessary.

This invention consists in the details of construction and in the combination and arrangements of the several parts of my improved locking device, whereby certain important advantages are attained, and the device is rendered simpler, less expensive, and otherwise more convenient and advantageous for use, all as will be hereinafter more fully set forth.

The novel features of my invention will be carefully defined in the appended claims.

In order that my invention may be better understood, I will now proceed to describe the same with reference to the accompanying drawing, wherein like reference characters designate corresponding parts, and in which—

Figure 1 is a top plan view of an embodiment of my invention, showing the projections of the collar in position to receive the pliable key, which is adapted to hold them in locked position. Fig. 2 is a view similar to Fig. 1, showing the collar turned "home"

and locked. Fig. 3 is a sectional view taken substantially on the line 3—3 of Fig. 2. Fig. 4 is a top plan view similar to Fig. 1, showing my invention applied to the conventional threaded bolt and nut. Fig. 5 is a sectional view taken substantially on the line 5—5 of Fig. 4.

As described in Figs. 1 to 3, A designates a shank of any ordinary or preferred construction, having a transverse channel or cavity 1, which may be of a configuration to suit the necessary requirements, said cavity or channel being herein disclosed as a hole produced in an end of the shank. Adapted to surround the shank A, is the collar B, having upon a face thereof the projections 2, placed at predetermined intervals and affording the cavities or channels 3, which are adapted to receive the extremities of the pliable key 4, when said key is in applied position. To lock the collar B to the shank A, position the pliable key 4 in the cavity or channel 1 of the shank A with the extremities thereof within the cavities or channels 4 of the collar B, as is illustrated in Fig. 1. As is thought to be obvious, upon the relative rotation of the shank and collar, the pliable key 4 will be drawn through the cavities or channels afforded by the projections 2 and brought in contact with, and partly embracing, the shank A, as is shown in Fig. 2. Since the pliable qualities of the key are exempt from all vibratory influences, the collar can be removed only by returning the collar B to its original position with relation to the shank A.

In Figs. 1 to 3, I have shown the shank A as smooth and unobstructed, as I have found in practice with this arrangement my invention operates with facility, but I also intend that my invention be employed to lock a bolt and a co-acting nut, as is shown in Figs. 4 and 5, wherein the construction and arrangement of the various parts are substantially identical to what has been previously described, and for this reason I have applied to Figs. 4 and 5, the same reference characters as applied to the preceding figures. In this form of my invention, however, it is to be noted that the intermediate portion of the key 4 is received within the threads 5 of the bolt A.

Any tool which can be used to manipulate the collar, is the only tool necessary to lock or remove the collar from its shank. The pliable locking key may vary in size inas-

much as precision is not necessary in the manufacturing of my locking device.

The extremely simple construction employed in the manufacture of my locking device makes economy an important feature of my invention.

From the foregoing description it is thought to be obvious that a locking device constructed in accordance with my invention is of an extremely simple and comparatively inexpensive nature, and is particularly well adapted for use by reason of the convenience and facility with which it may be assembled, and it will also be obvious that my invention is susceptible of some change and modification without material departure from the principles and spirit thereof, and for this reason I do not wish to be understood as limiting myself to the precise arrangement and formation of the several parts herein shown in carrying out my invention in practice, except as is defined by the scope of the claims appended hereto.

What I claim, is:

- 25 1. In combination with a shank having a cavity disposed transversely thereof, a collar adapted to surround the shank, said collar being provided with spaced channels positioned at predetermined intervals transversely thereof and having their inner extremities spaced from the bore of said collar, and a pliable key adapted to be inserted through the cavity of the shank with its extremities positioned within the channels of the collar.
- 30 2. In combination with a shank having a cavity disposed transversely thereof, a collar adapted to surround the shank, said collar being provided with spaced channels positioned at predetermined intervals transversely thereof and having their inner extremities spaced from the bore of said collar, and a pliable key adapted to be inserted through the cavity with its extremities positioned within the spaced channels of the collar, said key being of such a length as to

maintain its extremities within the spaced channels of the collar upon relative rotation of said shank and collar.

3. In combination with a shank having 50 a cavity disposed transversely thereof, a collar adapted to surround the shank, said shank and collar being capable of relative axial rotation, said collar being provided with channels having their inner extremities spaced from the bore of said collar, said channels of the collar and the cavity of the shank being adapted to initially register, and a pliable key inserted in the cavity and within the channels when said cavity and 60 channels are in register.

4. In combination with a shank having a cavity disposed transversely thereof, a collar adapted to surround the shank, said shank and collar being capable of relative 65 axial rotation, said collar being provided with channels having their inner extremities spaced from the bore of said collar, said channels of the collar and cavity of the shank being adapted to initially register, 70 and a pliable key inserted in the cavity and within the channels when said cavity and channels are in register, said key being adapted to be flexed exteriorly of the shank upon relative rotation of the shank and 75 collar.

5. In combination with a threaded shank having a cavity disposed transversely thereof, a nut adapted to coact with said shank, said nut being provided with spaced projections on a face thereof, and a pliable key adapted to be positioned within the cavity of the shank and between the projections of the nut, said projections being so positioned as to force the key in close proximity with 85 the threads of the shank upon relative rotation of the shank and nut.

OSCAR V. PAYNE.
